POWER OPERATED KNIFE HANDLE

Arnold O. Wolf, 1509 Rapids Drive, Racine, Wis.

Filed May 21, 1965, Ser. No. 85,390

Term of patent 14 years

(Cl. D22—3)

FIG. 1

FIG. 2

FIG. 3

FIG. 4

FIG. 5

FIG. 1 is an elevational side view of a power operated knife handle, showing my new design.

FIG. 2 is a top plan view thereof.

FIG. 3 is a bottom view thereof.

FIG. 4 is an elevational end view thereof as seen from the left; and

FIG. 5 is an elevational end view thereof as seen from the right.

The fragmentary broken line showing of the knife blade in FIGS. 1, 2 and 3 is for illustrative purposes only.

I claim:

The ornamental design for a power operated knife handle, substantially as shown and described.
